(57) **CLAIM**

The ornamental design for a toy with light projection and storytelling as shown and described.

DESCRIPTION

FIG. 1 is a top, front, and right side perspective view of a toy with light projection and storytelling according to the present design;

FIG. 2 is a bottom, rear, and left side perspective view of the toy with light projection and storytelling according to the present design;

FIG. 3 is a front elevation view of the toy with light projection and storytelling according to the present design;

FIG. 4 is a rear elevation view of the toy with light projection and storytelling according to the present design;

FIG. 5 is a left side view of the toy with light projection and storytelling according to the present design;

FIG. 6 is a right side view of the toy with light projection and storytelling according to the present design;

FIG. 7 is a top plan view of the toy with light projection and storytelling according to the present design; and,

FIG. 8 is a bottom plan view of the toy with light projection and storytelling according to the present design.

The broken lines in the drawings depict portions of the toy with light projection and storytelling that form no part of the claimed design.

1 Claim, 7 Drawing Sheets
